UNITED STATES PATENT OFFICE

2,675,062

CHAIR AND TABLET ARM ASSEMBLY

John H. Clarin, Oak Park, Ill., assignor to Clarin
Mfg. Co., Chicago, Ill., a corporation of Illinois

Application August 17, 1951, Serial No. 242,248

13 Claims. (Cl. 155—125)

1

This invention relates to chairs having tablets attached thereto and more specifically relates to a folding chair having a collapsible tablet mounted thereon which may be easily extended to a writing position, moved to a position so as to permit easy access to and departure from the chair, or collapsed to a storage position without detachment from the chair.

In the past, chairs have been provided with tablet arms for writing purposes. These tablet arms are usually held in fixed relation with respect to the associated chairs so that it is often difficult to sit down in and get up from the chairs, particularly when the chairs are in close relation to one another as in the class room. In addition, these tablet arms cannot be easily moved, if at all, when desired. In those chairs which provide collapsible tablet arms, the tablets are often unsteady and do not permit easy access to the chair without complete collapse of the tablet arm. Furthermore, it is usually difficult to collapse these tablet arms. Attempts have been made to place collapsible tablet arms on folding type chairs but these attempts have, in general, resulted in unsatisfactory constructions and the tablet arms were not sufficiently steady for satisfactory use.

Therefore, a main object of the present invention is to provide a chair having a tablet arm which may be extended for writing or other purposes, moved to such a position as to provide easy access to and withdrawal from the chair, and collapsed to a storage position removed from any interference with movement of the occupant of the chair. Another object of the invention is the provision of such a tablet arm which is associated with a folding chair so as to provide a sturdy overall construction of high rigidity. Still further objects are to provide a simple collapsible tablet arm assembly which may be easily and economically manufactured; the provision of a tablet arm assembly which may be operated with facility to permit access of a person to the chair and to permit an occupant to get up from the chair without difficulty and which may be extended or collapsed with ease; the provision of a tablet arm assembly which may be collapsed while a folding chair is extended or collapsed concurrently with folding of such a chair; to provide an assembly which may be compactly stored so as to facilitate stacking of the associated chairs; and the provision of a new and improved construction for accomplishing the foregoing objects of the invention.

The accompanying drawings illustrate a preferred embodiment of the invention in which:

2

Figure 1 illustrates a folding chair having a tablet arm assembly in accordance with the invention attached thereto, the tablet being shown in dotted lines in a position which permits easy access to the chair.

Figure 2 is a view similar to Fig. 1, the tablet arm assembly being shown in a collapsed position.

Figure 3 is a fragmentary plan view of the tablet arm assembly, the tablet being pivoted to the vertical position shown by dotted lines in Fig. 1.

Figure 4 is a side elevational view of the chair and tablet arm assembly.

Figure 5 is a fragmentary view, in side elevation, of the tablet arm assembly and chair, the view illustrating an intermediate position of the assembly as it is being collapsed.

Figure 6 is also a fragmentary view, in side elevation, of the tablet arm assembly showing another intermediate position of the assembly as it is being collapsed.

Figure 7 is a sectional view taken along line 7—7 in Figure 4.

The present invention is adapted for use in association with rigid chairs of various types but has particular adaption in connection with folding type chairs. Accordingly, the drawings illustrate a folding chair 1 on which is mounted a tablet arm assembly 2 in accordance with the invention.

The chair is of conventional construction and is generally similar to that shown in my patent, 2,548,098, entitled Folding Chair and Kneeler Attachment and issued on April 19, 1951, which patent has been assigned to the assignee of the present invention. As shown in the drawings, the chair 1 comprises a generally U-shaped section 3 which embraces the chair back 4. The U-shaped section is formed from a flat strip, the edges being rolled inwardly to provide a bead 5 and a section which is generally channel-shaped in cross-section. The lower portion of the U-shaped section 3 provides a pair of forward legs 6 for the chair 1 and these legs are interconnected by a cross brace 7 which is of similar construction as the U-shaped section 3 and which is usually riveted to the legs 6. In order to substantially prevent lateral or swaying movement of the chair 1 and assure more rigid construction, angularly extending braces 8 are connected between the cross brace 7 and each leg 6, as is particularly shown in Figs. 1 and 2. A seat supporting brace 9 is also connected between the legs 6 and is adapted to support a seat 10 when the chair is in its extended position.

The chair 1 further includes a pair of rear legs

11 which are fabricated from channel shaped sections 11a and plate sections 12 which extend upwardly from the channel sections. The plate sections nest in the channel sections and are usually riveted thereto. The rear legs 11 are pivotally connected to the front legs 6 of the chair as shown at 13 and the upper ends of the rear legs 11 are connected to the seat 10 by means of pivots. Cross braces 14 and 15 extend between the rear legs 11 in order to provide a 10 sturdy, reinforced construction.

The seat 10 in addition to being connected to the upper end of the rear legs 11 and supported by the cross-brace 9 when the chair is extended is also suspended from the U-shaped section 3 by means of links 16 which are pivotally connected to the U-shaped section as shown at 17 and to the seat as indicated at 18. The lower end of the link 16 extends below the seat to provide an ear 19 which engages the cross brace 9 and limits the unfolding movement of the chair. A pin 20 projects from each side of the seat 10 and is positioned to engage the ear 19 so as to limit the unfolding movement of the seat and permit easy unfolding action.

The tablet arm assembly 2 is adapted to be collapsed and to be extended to its writing position at any time when the chair is extended. Furthermore, the assembly 2 is operable to permit easy access to the chair or an occupant to leave the chair without difficulty. As shown in the drawings, the assembly is disposed on the right hand side of the folding chair but it may be attached to the left hand side of the chair.

The tablet arm assembly includes a tablet arm 21 which is carried on a frame 22. When the assembly 2 is extended, the frame extends forwardly from the chair, as shown in Fig. 4, and is supported in this position by a supporting member 23 and a linkage 24. The supporting member and linkage are each connected to the U-shaped section 3. The tablet arm assembly 2 is secured in its extended position by a releasable locking mechanism 25 which is associated with the assembly 2.

The tablet arm 21 will usually be made of wood, though other materials may be used, and is shaped to provide an enlarged forward section for writing purposes and to permit the chair occupant to comfortably sit in the chair. A pair of angle members 26 are attached to the underside of the tablet arm and are adapted for connection to the frame 22. The connection to the frame is provided by rivets 27 which permit the tablet to be tilted to an out-of-the-way position, as shown by the dotted lines in Fig. 1, thereby facilitating access to the chair and permitting an occupant to leave the chair. As a result of this feature, the chairs may be placed in close relation to one another without inconveniencing the chair users.

The tablet arm supporting frame 22 may be fabricated from a strip of material, as shown in Fig. 3, the strip being formed to provide a rectangular section 28, which is disposed under the tablet 21 and which prevents any tilting of the tablet when in the writing position. The strip is further formed to provide a section 29 which extends rearwardly from the rectangular section 28 and connects to linkage 24. The rearward-most edge of this section is provided with a shoulder 30 which is in position to engage the linkage 24 when the tablet arm assembly 2 is collapsed. The frame 22 is pivotally connected to the upper end of the supporting member 23 by means of a pin 31, and is also connected to the 75

supporting member by means of a diagonally extending support brace 32 which extends from the outer edge of the frame 22 diagonally inwardly to the supporting member 23.

The supporting member 23 comprises an angle iron section in the construction shown in the drawings, and the lower end of this member is provided with a slot 33 which permits limited up and down movement of the member. A pin 34 is attached to the right leg 6 for engaging the slot 33, this pin being supported on a plate 35 which is nested in the channel section of the leg 6, as shown in particular in Fig. 4.

The linkage 24, as before indicated, is connected to the rearward end of the frame 22 and comprises a link 36 which is pivotally connected to the U-shaped section 3 at its upper end and to the frame 22 adjacent its lower end, when the assembly 2 is extended. The link extends below the frame to provide a pawl 37 as shown in Fig. 4. The pawl is proportioned to engage the shoulder 30 on the end of the frame 22 so as to prevent over-center movement of the link when the tablet arm assembly 2 is collapsed. If such over-center movement is permitted, the assembly 2 may be difficult to extend. A dog 38 is secured to the U-shaped section 3 for the purpose of engaging the pawl 37 when the assembly is in the extended position. This is an important feature of the invention and prevents lateral movement of the rearward end of the tablet arm 21 thereby providing a very steady surface. The dog 38 is desirably also positioned to engage the supporting member 23 when the tablet arm assembly 2 is collapsed.

When the chair shown in the drawings is used in combination with the tablet arm assembly, it is necessary to build out the U-shaped section 3 for purposes of supporting the linkage 24 and this is accomplished through provision of an arcuate shaped piece 39 which is riveted or otherwise attached to the upper end of the U-shaped section 3. The link 36 is connected to this piece.

The releasable locking mechanism 25 as shown in the drawings is also an important feature of the invention as it permits the tablet arm assembly 2 to be collapsed when the chair is in the unfolded position and causes the assembly to collapse when the chair is folded. The locking mechanism 25 includes a channel-shaped latch 40 which is fixedly attached to the supporting member 23 and opens inwardly toward the chair (Fig. 3). The latch includes a pair of legs 40a and 40b, the leg 40b being secured to the supporting member 23. The locking mechanism 25 further includes an irregularly shaped catch 41 which, in the construction shown in the drawings, is formed on the upper end of the plate 12 associated with the right rear leg 11. (Figures 4, 5 and 6.) The catch 41 is provided with a cam surface 42 which inclines forwardly and downwardly from the supporting member 23 (Fig. 4) and which is positioned to engage the leg 40a of the latch 40. The catch 41 is also provided with a V-shaped notch 43 which is in position to receive the supporting member 23. The notch 43 is formed in a portion of the catch 41 which extends generally parallel to the rear leg 11 and which provides a second cam surface 44. The releasable locking mechanism is shown in the locked position in Fig. 4 and, in this position, the supporting member 23 is seated in the notch 43 and the latch 40 engages the cam surface 42. As a result, the supporting member is secured against both lateral, and forward and rearward

movement by the notch 43, and latch 40 and catch 41 respectively. Through engagement of the pawl 37 on the linkage 24 with the dog 38 and the action of the locking mechanism 25, the tablet 21 is securely held in the writing position thereby providing an unusually steady writing surface.

The cam surface 42, notch 43, and slot 33, which is formed in the lower end of the supporting member 23, are proportioned and arranged so that the supporting member may be lifted and rotated rearwardly to thereby disengage the latch 40 from the catch 41. The cam surface 42 and latch 40 are also proportioned so that when the chair is collapsed the latch 40 slides down the cam surface 42 and the catch 41 moves upwardly through the latch 40 so that the latch disengages from the cam surface 42, thereby releasing the locking mechanism and causing the tablet arm assembly 2 to collapse. When the latch 40 disengages the cam surface 42 it slides down the second cam surface 44 on the catch 41, this second surface extending downwardly and rearwardly from the lower edge of the cam surface 42, as before indicated. It is important that this surface be proportioned so that the latch 40 disengages therefrom prior to complete collapse of the assembly 2. If such disengagement is not accomplished, the assembly will extend when the chair is unfolded placing undesired stress upon various parts of the assembly and making the chair difficult to unfold.

In order to collapse the tablet arm assembly 2 when the chair is in the extended position, the tablet arm 21 is first tilted to the position shown by dotted lines in Figure 1 and then the supporting member 23 is lifted to the position shown in Figure 5 so as to disengage the latch 40. The assembly is moved rearwardly, the supporting member moving to the position shown in Fig. 6 and the link 36 rotating rearwardly. Upon continued rearward movement of the assembly, the supporting member 23 engages the dog 38 on the U-shaped member 3 thereby limiting the collapsing movement of the tablet arm assembly 2 and the pawl 37 on the link 36 engages the shoulder 39 on the frame 22 to prevent over-center movement of the linkage 24.

When the chair 1 is folded and the tablet arm assembly 2 is extended, the catch 41 moves upwardly and rearwardly relative to the latch 40 causing the latch to slide down the cam surface 42 and become disengaged therefrom. Further collapsing movement of the chair causes the latch to slide down the cam surface 44 and disengage therefrom. The tablet arm assembly then collapses to the position previously described. The tablet arm 21 may be tilted as desired. When the chair 1 is unfolded, the tablet arm assembly 2 remains collapsed. The assembly may be extended from this collapsed position by merely pulling the assembly forward, lifting the supporting member up to engage the latch 40 with the catch 41, and then lowering the latch 40 into engagement with the catch.

The arrangement described in the foregoing provides an unusually steady construction and at the same time is simple to manufacture. Furthermore, the arrangement permits easy access and departure of occupants to and from the chair and collapse of the tablet arm assembly to an out-of-the-way position when desired. The assembly may be easily and simply operated to any desired position and may be made a part of a folding chair so that the combined chair and assembly may be easily stored. Various of the

novel features of the invention are defined by the following claims.

I claim:

1. In combination a chair, and a collapsible tablet arm assembly, said tablet arm assembly comprising a tablet arm which extends forwardly from said chair when said assembly is in the extended position, a linkage connected to the rearward portion of said tablet arm and to said chair for pivotally connecting said tablet arm to said chair, a supporting member pivotally connected at one end to said tablet arm forwardly of said linkage and at the other end to said chair at a point located below the point of connection of said one end for holding said tablet arm in an operative horizontally extended position, and releasable locking means securing said assembly in an extended position and permitting said assembly to be collapsed.
2. In combination, a chair and a collapsible tablet arm assembly, said tablet arm assembly including a tablet arm which extends forwardly from said chair, when said tablet arm assembly is extended, a frame which supports said tablet arm, means for pivotally connecting said tablet arm to said frame, said pivot means having a forwardly extending horizontally disposed axis so as to thereby permit said tablet arm to be tilted from a horizontal position to a vertical position, a linkage connected to the rearward portion of said frame and to said chair, a supporting member pivotally connected at one end to said frame at a point forwardly of said linkage and at the other end to said chair at a point below the point of connection to said frame, and releasable locking means securing said assembly in an extended position and permitting said assembly to be collapsed.
3. In combination, a chair and a collapsible tablet arm assembly, said tablet arm assembly comprising a tablet arm which extends forwardly from said chair when said assembly is extended, a linkage connected to said chair and to the rearward portion of said tablet arm for pivotally connecting said tablet arm to said chair, a supporting member pivotally connected at one end to said tablet arm forwardly of said linkage and at the other end to said chair at a point located below the point of connection of said one end, and releasable locking means securing said assembly in an extended position and permitting said assembly to be collapsed, said locking means including a latch which is attached to said supporting member and a coacting catch secured to said chair.
4. In combination a chair, and a collapsible tablet arm assembly, said tablet arm assembly including a tablet arm which extends forwardly from said chair when said assembly is extended, a frame which supports said tablet arm, means for pivotally connecting said tablet arm to said frame, said pivot means having a forwardly extending horizontally disposed axis so as to thereby permit said tablet arm to be tilted from a horizontal position to a vertical position, a linkage connected to the rearward portion of said frame and to said chair, a supporting member pivotally connected at one end to said frame at a point forwardly of said linkage and at the other end to said chair at a point below the point of connection to said frame, and releasable locking means securing said assembly in an extended position and permitting said assembly to be collapsed, said locking means including a latch which is attached to said supporting mem-

ber and a coacting catch which is secured to said chair, said catch having a rearwardly opening notch formed therein engaging said supporting member and a portion engaging said latch when said supporting member is disposed in said notch to thereby secure said supporting member against forward and rearward movement.

5. In combination a chair, and a collapsible tablet arm assembly, said tablet arm assembly including a tablet arm which extends forwardly from said chair when said assembly is extended, a frame which supports said tablet arm, means for pivotally connecting said tablet arm to said frame, said pivot means having a forwardly extending horizontally disposed axis so as to thereby permit said tablet arm to be tilted from a horizontal position to a vertical position, a linkage connected to the rearward portion of said frame and to said chair, a supporting member pivotally connected at one end to said frame at a point forwardly of said linkage, the other end of said supporting member having a slot formed therein, a pin attached to said chair and slidably engaging said slot in said supporting member, and releasable locking means securing said assembly in an extended position and permitting said assembly to be collapsed, said locking means including a latch which is attached to said supporting member, and a coacting catch which is secured to said chair, said catch having a rearwardly opening notch formed therein engaging said supporting member and a portion engaging said latch when said supporting member is disposed in said notch to thereby secure said supporting member against forward and rearward movement, said slot in said supporting member being proportioned to permit said latch to engage and disengage said catch.

6. In combination a chair, and a collapsible tablet arm assembly, said tablet arm assembly including a tablet arm which extends forwardly from said chair when said assembly is extended, a frame supporting said tablet arm, means for pivotally connecting said tablet arm to said frame, said pivot means having a forwardly extending horizontally disposed axis so as to thereby permit said tablet arm to be tilted from a horizontal position to a vertical position, a linkage connected to the rearward portion of said frame, said linkage including a link which is pivotally connected at one end to said chair and at the other end to said frame, a dog secured to said chair engaging said link when said assembly is extended, a supporting member pivotally connected at one end to said frame at a point forwardly of said linkage and at the other end to said chair at a point below the point of connection to said frame, and releasable locking means securing said assembly in an extended position and to permit said assembly to be collapsed.

7. In combination a chair, and a collapsible tablet arm assembly, said tablet arm assembly including a tablet which extends forwardly from said chair when said assembly is extended, a frame supporting said tablet, means for pivotally connecting said tablet to said frame, said pivot means having a forwardly extending horizontally disposed axis so as to thereby permit said tablet to be tilted from a horizontal position to a vertical position, a linkage connected to the rearward portion of said frame, said linkage including a link pivotally connected at one end to said chair, the other end of said link providing a pawl, pivot means for interconnecting said link

to said frame, a dog secured to said chair and positioned to engage said pawl when said assembly is extended and to prevent lateral movement of said frame, a supporting member pivotally connected at one end to said frame at a point forwardly of said linkage and at the other end to said chair at a point below the point of connection to said frame, and releasable locking means securing said assembly in an extended position and permitting said assembly to be collapsed.

8. In combination a chair, and a collapsible tablet arm assembly, said tablet arm assembly including a tablet arm which extends forwardly from said chair when said assembly is extended, a frame supporting said tablet arm, means for pivotally connecting said tablet arm to said frame, said pivot means having a forwardly extending horizontally disposed axis so as to thereby permit said tablet to be tilted from a horizontal position to a vertical position, a linkage connected to the rearward portion of said frame, said linkage including a link pivotally connected at one end to said chair, the other end of said link providing a pawl, a pivot for interconnecting said link to said frame, a shoulder on the rearward end of said frame positioned to engage said pawl when said assembly is collapsed and prevent over-center movement of said linkage, a supporting member pivotally connected at one end to said frame at a point forwardly of said linkage and at the other end to said chair at a point below the point of connection to said frame, and releasable locking means securing said assembly in an extended position and to permit said assembly to be collapsed.

9. In combination a chair, and a collapsible tablet arm assembly, said tablet arm assembly including a tablet arm which extends forwardly from said chair when said assembly is extended, a frame supporting said tablet arm, means for pivotally connecting said tablet arm to said frame, said pivot means having a forwardly extending horizontally disposed axis so as to thereby permit said tablet arm to be tilted from a horizontal position to a vertical position, a linkage connected to the rearward portion of said frame, said linkage including a link pivotally connected at one end to said chair, the other end of said link providing a pawl, a pivot for interconnecting said link to said frame, a dog secured to said chair and positioned to engage said pawl when said assembly is extended to prevent lateral movement of said frame, a shoulder on the rearward end of said frame and positioned to engage said pawl when said assembly is collapsed so as to prevent over-center movement of said linkage with respect to said frame, a supporting member pivotally connected at one end to said frame at a point forwardly of said linkage and at the other end to said chair at a point below the point of connection to said frame, and releasable locking means securing said assembly in an extended position and permitting said assembly to be collapsed.

10. In combination a folding chair, and a collapsible tablet arm assembly, said tablet arm assembly comprising a tablet arm which extends forwardly from said chair when said assembly is in the extended position, a linkage connected to the rearward portion of said tablet arm and to said chair for pivotally connecting said tablet arm to said chair, a supporting member pivotally connected at one end to said tablet arm forwardly of said linkage and at the other end to said chair at a point located below the point of connection of said one end, and releasable lock-

ing means securing said assembly in an extended position and to permit said assembly to be collapsed.

11. In combination a folding chair, and a collapsible tablet arm assembly, said tablet arm assembly comprising a tablet arm which extends forwardly from said chair when said assembly is in the extended position, a linkage connected to the rearward portion of said tablet arm and to said chair for pivotally connecting said tablet arm to said chair, a supporting member pivotally connected at one end to said tablet arm forwardly of said linkage and at the other end to said chair at a point located below the point of connection of said one end, and releasable locking means securing said assembly in an extended position and to permit said assembly to be collapsed, said locking means including a channel-shaped latch attached to said supporting member and opening inwardly toward said chair, and a catch attached to said chair and having a rearwardly opening notch formed therein engaging said supporting member and having a cam surface for engaging a leg of said latch.

12. In combination a folding chair, and a collapsible tablet arm assembly, said tablet arm assembly comprising a tablet arm which extends forwardly from said chair when said assembly is in the extended position, a linkage connected to the rearward portion of said tablet arm and to said chair for pivotally connecting said tablet arm to said chair, a supporting member pivotally connected at one end to said tablet arm forwardly of said linkage and at the other end to said chair at a point located below the point of connection of said one end, said other end of said supporting member having a slot formed therein, a pin attached to said chair and slidably engaging said slot, and releasable locking means securing said assembly in an extended position and to permit said assembly to be collapsed, said locking means including a channel-shaped latch fixedly attached to said supporting member, and opening inwardly toward said chair, and a catch having a rearwardly extending notch formed therein for receiving said supporting member and having a cam surface positioned to engage a leg of said

latch, said slot in said supporting member being proportioned to permit said latch and catch to be engaged and disengaged.

13. In combination a folding chair comprising pairs of front and rear legs hingedly connected together and shiftable into and out of collapsed and extended positions, a seat pivoted on said rear legs, said front legs supporting said seat when said chair is unfolded, and a tablet arm assembly adapted to be collapsed when said chair is folded and also when said chair is unfolded, said tablet arm assembly comprising a tablet arm which extends forwardly from said chair when said assembly is in the extended position, a linkage connected to the rearward portion of said tablet arm and to said chair for pivotally connecting said tablet arm to said chair, a supporting member pivotally connected at one end to said tablet arm forwardly of said linkage and at the other end to said chair at a point located below the point of connection of said one end, said supporting member having a slot formed therein, a pin on the lower portion of said front legs and engaging said slot, and releasable locking means which permits said assembly to be collapsed, said locking means including a channel-shaped latch fixedly attached to said supporting member intermediate its ends, and opening inwardly toward said chair, and a catch attached to the upper end of one of said rear legs and having a rearwardly opening notch formed therein and a cam surface engaging said latch, said cam surface being proportioned so that said latch disengages therefrom when said chair is folded whereby said assembly collapses when said chair is folded, said slot in said supporting member being proportioned to permit said latch to be disengaged from said catch and said assembly to be collapsed.
